UNITED STATES PATENT OFFICE

103,971

DESIGN FOR AN IRONING BOARD SUPPORT

Udo K. Johannsen, Cortland, N. Y., assignor to
The Brewer-Titchener Corporation, Cortland,
N. Y., a corporation of New York

Application June 13, 1936, Serial No. 63,274

Term of patent 7 years

To all whom it may concern:

Be it known that I, Udo K. Johannsen, a subject of the Kingdom of Denmark and a resident of the city of Cortland, in the county of Cortland and the State of New York, have invented a new, original, and ornamental Design for an Ironing Board Support, of which the following is a specification, reference being had to the accompanying drawing forming part thereof, in which:

Fig. 1 is a front view of an ironing board support showing my new design, and

Fig. 2 is a side view thereof.

I claim:

The ornamental design for an ironing board support, as shown.

UDO K. JOHANNSEN.
